SHIRT

Filed Nov. 4, 1942

INVENTOR,
SOLOMON EPSTEIN.
By Martin P. Smith, Atty.

UNITED STATES PATENT OFFICE

134,838

DESIGN FOR A SHIRT

Solomon Epstein, Los Angeles, Calif.

Application November 4, 1942, Serial No. 108,695

Term of patent 3½ years

To all whom it may concern:

Be it known that I, Solomon Epstein, a citizen of the United States and resident of Los Angeles, county of Los Angeles, State of California, have invented a new, original, and ornamental Design for Shirts, of which the following is a specification, reference being had to the accompanying drawing, forming a part thereof.

Fig. 1 is a front elevational view of a shirt showing my new design.

Fig. 2 is a rear elevational view of the shirt.

I claim:

The ornamental design for a shirt, as shown.

SOLOMON EPSTEIN.
